CATHODE-GRID ASSEMBLY FOR
CATHODE-RAY TUBESJoseph Kelar, Lancaster, Pa., assignor to Radio
Corporation of America, a corporation of Delaware

Application June 27, 1947, Serial No. 757,633

7 Claims. (Cl. 250—27.5)

1

My invention relates to cathode ray tubes, and in particular to an electron gun structure having an improved cathode-grid unit assembly for such tubes.

A conventional type of cathode ray tube has an electron gun structure comprising a tubular cathode enclosing a heater filament and spaced critically from a control grid. Axially spaced along the gun from the control grid is a focusing grid plate, a first anode cylinder and a second anode cylinder. These structures when maintained at appropriate electrostatic potentials form a series of bi-potential electron lenses which tend to form the electron emission from the cathode into a beam and accelerate and focus the beam on a fluorescent screen at the end of the tube.

The construction of the cathode-grid structure of a conventional type of electron gun has always involved the difficult process of assembling, by hand operation, many small parts in the proper relationships. The process also involves the fixing of several subassemblies in a predetermined spaced relationship involving critical distances conforming to small tolerances.

In practice, subassemblies and spacer elements are found to vary considerably in their critical dimensions and are consequently "matched" to provide the desired cathode grid spacing. The procedure of "matching" has consisted of sorting cathode subassemblies into several groups, of which each group includes cathode subassemblies conforming within close tolerances to a specific dimension. The cathode to grid ceramic spacers are also divided into a like number of groups each of which contains spacers conforming within close tolerances to a specific dimension. Each group of cathode subassemblies is then "matched" with one of the groups of spacers so that when a cathode subassembly and a spacer of matched groups are assembled in a grid cylinder, there will result a cathode-grid structure having a close approximation of the predetermined cathode to grid spacing. Such a process of "matching" is time consuming and involves continuous checking which process does not lend itself to quantity production.

Conventionally, the control grid and focusing grid are held in a predetermined spaced relationship by a jig and then mounted on ceramic side rods or by supports fused in a glass bead. Such a procedure places parts of the grid supporting structure under strains which, when upon removal of the jig, causes a change in the relative spacing of the two grids. Inaccuracies in this grid spacing produce variations in the control grid cut-

2

off voltage. It is necessary that these cutoff voltages be within certain limits. A large variation from the required voltage indicates a poor gun structure which must be discarded.

5 In the conventional design of control grid the electrode consists of a cylinder having an apertured disc closing one end thereof. This grid cylinder is used to support a cathode structure. Also, this grid assembly presents a large area to the other electrodes in the electron gun, and thus results in a large input capacitance. Such a large input capacitance is a serious disadvantage especially for applications in which a high frequency signal is impressed on the control grid as in television applications.

10 It has also been the practice to bring the ends of the heater filament out through the lower open end of the gun structure over the center of the tube stem. Due to its fragile construction, the heater filament is mounted separately by welding to the stem leads after the rest of the gun structure has been mounted on the tube stem. Due to close spacing between the gun and the tube stem, it has been difficult to insert a welding tool in 15 this space for joining the filament to its leads. Furthermore, it is desirable to mount the gun structure close to the tube stem to provide as short a neck as possible for the cathode ray tube. Such close mounting of the gun structure to the 20 tube stem is prevented by the conventional filament mounting.

25 It is, therefore, an object of my invention to provide an electron gun structure comprising few parts and whose dimensions are not limited by close tolerances.

30 Another object of my invention is to provide an electron gun structure designed for rapid assembly.

35 It is another object of my invention to provide a gun structure comprising a plurality of subassemblies of simplified design.

40 It is also an object of my invention to provide an electron gun structure having accurate grid-cathode and control grid to focusing grid spacings.

45 Another object of my invention is to provide an electron gun structure designed to permit close mounting to the tube stem.

Another object of my invention is to provide a gun structure incorporating a heater subassembly supported entirely within said gun structure.

The novel features which I believe to be characteristic of my invention are set forth with particularity in the appended claims, but the invention itself will best be understood by reference

to the following description taken in connection with the accompanying drawing, in which:

Fig. 1 is a partial sectional view in elevation of an electron gun structure according to my invention;

Fig. 2 is an elevational view in section of a cathode-grid assembly incorporating the novel structure of my invention;

Fig. 3 is an enlarged partial view of the control grid subassembly of Fig. 1;

Fig. 4 is an elevational view of the cathode filament subassembly of Fig. 1, according to my invention;

Figs. 5 and 6 are elevational sectional views of a control grid assembly according to modifications of my invention; and

Fig. 7 illustrates a device for fixing the cathode sleeve to its support ceramic.

Referring to Fig. 1 there is illustrated an electron discharge tube of the cathode ray type having an envelope 10, preferably of glass, closed at one end by a stem press 12. Mounted within the tubular envelope 10 is an electron gun structure, to be described, for accelerating and focusing a beam of electrons on a fluorescent screen 11 at the other end 13 of the discharge tube. Such a structure illustrated in Fig. 1 may be incorporated in a cathode ray tube, for example. The end of the tubular envelope may be enclosed in a base element 14 if desired through which extend base pins 16. Sealed through the glass stem 12 of the tube 10 are a plurality of stem leads 18 for supporting the electron gun structure within the tubular portion 10 as well as for forming electrical conductor means between the base pins 16 and the respective leads to the electrodes of the gun structure. Mounted on two of the stem leads 18 are a pair of ceramic support rods 20 and 22. Fixed to the ceramic supports 20 and 22 is a grid support cylinder 24. Also mounted on the ceramic support rods 20 and 22 and spaced axially within the tubular envelope 10 from the support cylinder 24 is a first anode electrode comprising a cylinder 26.

Within the tubular grid support 24 are mounted a plurality of electrodes in a manner disclosed in detail in Fig. 2. As shown in Fig. 2 the upper end of the grid cylinder 24 is closed by a circular plate 30 having an aperture 32 in the center thereof. The apertured plate 30 comprises a grid structure which is utilized as the second or shield grid of the electron gun. The tubular grid 24 has an opening or aperture 25 in the side wall thereof, the purpose of which will be explained below. This opening 25 in the preferred form shown in Figs. 1 and 2 extends from the lower edge of the tubular electrode 24 to a predetermined distance below the top edge of the electrode. Mounted within the support electrode 24 is a ceramic disc 34 having a peripheral ridge portion 35 extending above the upper surface of the disc 34 and held in abutment against the under surface of the apertured plate 30.

As shown in detail in Fig. 3 the disc 34 has at its center an apertured opening 41 coaxial to the shield grid opening 32. The under surface of the ceramic disc 34 is machined to form a recess 45 coaxial with the aperture 41 and having a greater diameter than the recess 41. A control grid is mounted within the apertures 41 and 45 of the ceramic disc 34. The preferred form of the control grid is shown in Figs. 2 and 3. This control grid comprises a grommet or eyelet 44 fitted into the aperture 41 of the supporting ceramic disc 34. Eyelet 44 preferably has a flanged

portion fixed by welding to a grid plate 42. Grid plate 42 is preferably a small circular disc having an aperture 43 at its center. Plate 42 is fitted into the recessed portion 45 of the ceramic disc and fixed to eyelet 44 so that aperture 43 is coaxial to the grid shield aperture 32. A control grid conductor lead 46 is fixed to the control grid plate 42 and extends from the grid plate out through the opening 25 in the side of the shield grid cylinder 24 as shown in Figs. 1 and 2.

Fixed immediately below the ceramic support disc 34 is a supporting ceramic cup 36. The ceramic cup 36 is arranged within the cylindrical electrode 24 so that the lip 39 of the cup is positioned in abutment against the lower surface of the ceramic disc 34. Through the bottom of the ceramic cup 36 is formed an aperture 37 at its center. Coaxially mounted within the central aperture 37 is a tubular cathode electrode 50. Cathode tube 50 is fixed to the ceramic support cup 36 by the forming of peripheral ribs or beadings 54 above and below the supporting portion of the cup 36. Beadings 54 are pressed out of the metal wall of the tubular cathode 50 and forced against the adjacent portions of the ceramic 36 so as to tightly lock the tubular cathode 50 to the support ceramic cup 36. The upper end of the cathode tube 50 is closed, as shown in Fig. 1 by a cap portion 52. Fig. 2 shows one form of a possible tubular cathode 50. However, it is possible to form the cathode 50 as a cup closed at one end by a drawing operation from a single piece of metal. The upper surface of the cathode cap 52 is usually coated by a mixture of the oxides of the alkaline earth metals to provide a source of electrons as is well known in the art. This activated surface of the cathode cap 52 is accurately spaced at a predetermined distance from the control grid 42. A cathode conductor lead 56 is fixed to the cathode sleeve 50 at 58 and extends radially through the aperture 25 in the side wall of the supporting shield grid cylinder 24.

To provide the desired amount of electron emission from the activated surface of the cathode cap 52, the cathode 50 is heated to an appropriate temperature. For this purpose a heater filament 60 is mounted so as to extend upwardly into the tubular cathode 50. The cathode heater filament 60 is mounted on a second ceramic cup 38 which is coaxially mounted within the supporting shield grid cylinder 24 in such a manner that the lip 53 of the ceramic cup 38 abuts against the lower surface of the cathode support cup 36. In the center region of the bottom of the ceramic cup 38 are formed two apertures 62 and 64 as shown in Figs. 2 and 4. A pair of heater filament leads 66 and 68 extend across the center region of the lower surface of the ceramic cup 38. The ends 70 and 72 respectively of heater leads 66 and 68 are respectively anchored within recesses 74 in the bottom of the ceramic 38 (Fig. 2). The opposite ends respectively of the heater leads 66 and 68 extend upwardly through apertures 75 and 77 (Fig. 4) within the wall portion of the ceramic cup 38.

To assemble the cathode heater filament within its support ceramic cup 38 the heater leads 66 and 68 are provided with a shape disclosed in Fig. 4. The ends 76 and 78 of the heater filament leads are threaded through the respective openings 75 and 77 in the ceramic cup wall until the other ends 70 and 72 are fitted tightly into the respective recesses 74 in the bottom of the ceramic cup 38. The ends 76 and 78 of the fila-

ment leads are then bent sharply at 90° so as to extend radially away from the center of the ceramic cup 38. Grooves 81 and 82 are provided in the upper surface of the ceramic cup 38 to respectively receive ends 76 and 78 of the filament leads flush to the upper surface of the cup lip. The filament ends 61 and 63 of heater filament 60, are threaded respectively through the openings 62 and 64 in the bottom of the ceramic 38. The filament ends 61 and 63 may be then respectively welded to the filament leads 66 and 68. This arrangement fixes the heater filament 60 between the leads 66 and 68. As shown in Fig. 4 an additional groove 57 is formed in the lip portion 53 of the ceramic cup 38. The groove 57 permits the passage therethrough of the cathode lead 56 and allows the lip surface 53 of the ceramic cup 38 to fit flush to the under surface of the first ceramic cup 36.

As shown in Fig. 2 the ceramic supports 34, 36 and 38 are locked together one against the other between the screen grid plate 30 and a flanged ring 48 which is pressed into the open end of the support cylinder 24 and welded to the sides thereof to tightly hold the several ceramics in position.

As shown in Fig. 2 the control grid 42 comprises a relatively small surface area. In the conventional design for an electron gun the control grid was formed as a supporting cylinder similar to the supporting grid cylinder 24 of Fig. 2. Such a supporting control grid cylinder presented a large area to the other electrodes within the gun and resulted in a large input capacitance. A large input capacitance is a serious disadvantage especially for applications in which a high frequency signal is impressed on the control grid as in television applications. The eyelet 44 and grid plate 42 of Figs. 2 and 3 present a much smaller surface area exposed to adjacent electrodes of the electron gun structure and thus eliminates the large input capacitance which is such a disadvantage in conventional gun structure.

Furthermore, in conventional electron gun construction, it has been a problem to obtain the correct spacing between the control grid and the second or screen grid to within close tolerances. Inaccuracies in this control grid-to-screen grid spacing produce variations in the control grid cutoff voltage. These cutoff voltages are required to be within certain limits and any large variation from the required voltages will produce a poor gun structure which frequently must be discarded. The particular construction shown in Fig. 2 provides a means and a method for accurately obtaining the required control grid-to-screen grid spacing. The ceramic disc 34 is preferably pressed out in a metal die from a pasty ceramic material. The discs are then fired after which they may be machined to provide the required shape. In the construction of the ceramic disc 34 there may be variations in the height of the rib 35 above the surface of the disc 34. The rib 35 forms a means for spacing the grid plate 42 from the screen grid plate 30. The variations in the ribs 35 of the ceramic disc 34 may be compensated for by the depth to which the recess 45 of disc 34 is machined out. This recess 45 can be machined very accurately to a depth within plus or minus 1 mil of the desired amount. That is, the depth to which the recess 45 is cut determines the spacing between the control grid plate 42 and the shield grid plate 30. This structural relationship of grid plates 30 and 42 pro-

vides a simple and accurate method for assembling the two grids relative to each other, with the desired spacing.

Figs. 5 and 6 disclose modifications in the form of the control grid structure disclosed in Figs. 2 and 3. In Fig. 5, for instance, the control grid takes the form of an eyelet 83 mounted on a ceramic disc 86. The eyelet or grommet 83 comprises a flanged portion 84 which is fitted into the recess 85 machined into the lower surface of supporting disc 86. The depth to which the recess 85 of ceramic disc 86 is machined determines the spacing between the control grid 88 and its corresponding shield grid. Eyelet 83 is firmly fixed to the ceramic support disc 86 by bending over a lip portion 87 in contact with the upper surface of the disc 86. This lip 87 of the eyelet 83 may be turned over by a spinning process. In this modification of Fig. 5 the grid eyelet 83 is made from solid stock and is machined to the desired shape.

In Fig. 6 a third modification of the control grid is shown in which a flanged eyelet 94 is inserted through a central aperture 95 of a supporting ceramic disc 90. The flanged portion of the eyelet 94 is welded either before or after its insertion in the aperture 95 to a grid plate 92 corresponding to plate 42 of Figs. 2 and 3. The grid plate 92 fits into the recess 91 machined to the desired depth in the under surface of the ceramic disc 90. The end of the eyelet 94 opposite to the flanged portion is flared over as at 93 to provide a locking means to firmly hold the control grid eyelet 94 to the ceramic 90. The upper edge of the aperture 95 of ceramic disc 90 may be bevelled off so as to accommodate the flared portion 93 of the eyelet 94.

In the several modifications of the type of control grid electrode disclosed in Figs. 2, 3, 5 and 6, the control grid to shield grid spacing is determined by the depth to which the recess in the under surface of the supporting ceramic is machined. As pointed out above, the recess can be formed to within very close tolerances and to a depth providing the required spacing between the two grids. Furthermore, the control grid supporting disc and the control grid eyelet may be assembled separately before insertion into the supporting grid cylinder 24.

50 In the conventional electron gun structure the cathode cylinder is customarily supported at the center of a ceramic disc and the disc in turn is spaced from the control grid plate by a metal or ceramic eyelet positioned therebetween. Previously, it has been found that variations in the size of the spacer members as well as variations in the relative position of the cathode sleeve to its supporting ceramic disc produce nonuniform cathode-control grid spacing.

60 The structure of Fig. 2 shows an improved method for mounting a cathode sleeve 50 relative to a control grid structure 42. It is desirable that the spacing between the top of the cathode electrode and the control grid conform to a predetermined amount and within rather small tolerances. In the construction shown in Fig. 2 the ceramic cup 36 forms both an insulating support for the cathode tube 50 as well as a means for spacing the cathode electrode from the control grid 42. With the construction of Fig. 2, the ceramic cup 36 need not be formed with any great accuracy. The cathode-to-control grid spacing is determined by the relative position of the cathode sleeve 50 to the top surface 39 of the cup lip. This spacing between the activated sur-

face of the cathode cap 52 and the top surface 39 of the cup lip may be accurately formed by the method shown in Fig. 7.

In Fig. 7 the cathode sleeve 50 may be assembled to the ceramic cup 36 by first inserting the open end of the cathode cup 50 through the aperture 30 in the bottom of the cup. The cup together with the cathode is then turned upside down on a polished metal surface 98 so that the lip 39 of the cup is flush with the surface 98. A spacer block 100 is placed between the cathode cap 52 and the polished surface 98. A tool inserted into the upper open end of the cathode sleeve 50 as shown in Fig. 7, forms the expanded peripheral rib 54 in the metal wall of the cathode tube. This tool consists of a sleeve 102 in which is slidably mounted a pin 104 having at its lower end a T-shaped head 106. Between the head 106 of pin 104 and the end of sleeve 102 is positioned a rubber ring or washer 108. The tool is inserted into the open end of the cathode cylinder 50 until the lower end of the sleeve 102 is approximately flush with the inner surface of the bottom of the ceramic cup 36 as is shown in Fig. 7. The T-headed pin 104 then is moved in an upwardly direction as indicated by the arrow while the sleeve 102 is maintained in position. The upward movement of pin 104 causes the T-shaped head 106 of the pin to compress the rubber washer 108. The rubber washer 108 is of such resiliency that the compression forces the sides of the cathode tube 50 outwardly in a radial direction to form a peripheral rib 54 which determines the position of the cathode sleeve 50 relative to the surface 39 of the lip of the ceramic cup 36. This relationship between the cathode sleeve 50 and the ceramic cup 36 can be varied to any desired amount by the use of another spacer block similar to block 100 having a different dimension. To accurately lock the cathode sleeve 50 to the ceramic 36 the tool may be withdrawn a sufficient amount away from the cathode sleeve 50 and another rib 54 pressed outwardly from the surface of the cathode tube 50 on the opposite side of the ceramic 36 so as to firmly lock the cathode sleeve 50 to the cup 36 and prevent any relative movement axially therebetween. Fig. 2 shows this arrangement.

The particular construction of the cathode assembly shown in Figs. 2 and 7 eliminates the use of several parts. Furthermore, this form of cathode assembly does not require the tedious process of matching a spacer to the particular cathode assembly conventionally used in order to provide the required cathode-to-grid spacing. Furthermore, as pointed out above the ceramic cup 36 need not be made to any close tolerances since the spacing between the activated surface of the cathode and the control grid plate is determined by the relative position of the activated surface of 52 to the surface 39 of the cup lip. This spacing is accurately obtained by the operation of assembling the cathode sleeve 50 to the ceramic cup 36 as disclosed in Fig. 7.

In the conventional type of electron gun construction the heater filament is usually mounted after the cathode grid assembly has been mounted on the glass stem of the discharge tube. Since the cathode heater filament is rather fragile the ends of the filament are welded or fixed to their respective leads after the cathode grid assembly has been mounted within the tube. Welding of the ends of the filament to their respective leads requires the inserting of a welding tool into the center portion of the tube stem between the cath-

ode grid assembly and the surface of the stem. The spacing of the gun parts during this operation is so close that the welding procedure is difficult. Furthermore, it also necessitates the positioning of the cathode grid assembly far enough above the surface of the glass stem so as to permit insertion of the appropriate welding tools.

In the particular construction shown in Figs. 2 and 4 the cathode filament may be assembled to its lead structure and to its supporting ceramic cup 38 separately before the gun structure shown in Fig. 2 is mounted on the tube stem 12.

The several electrode subassemblies shown in Fig. 2 are each assembled prior to their insertion in the supporting cylinder 24. After the grid plate 32 is mounted in the desired position in one end of the screen grid cylinder 24, the control grid assembly is positioned within the cylinder such that the rib portion 35 abuts against the lower surface of the grid plate 30. The ceramic cup 36 with the cathode electrode 50 accurately positioned therein is next inserted into the open end of the cylindrical electrode 34. Next, the second ceramic cup 38, with the cathode heater filament mounted thereon, is inserted into the cylindrical electrode 34 so that the cathode heater filament is positioned within the cathode sleeve 50. The second ceramic cup 38 is positioned so that the surface 53 of the cup lip is flush against the bottom surface of the first ceramic cup 36. The flanged locking ring 40 is then pressed into the open end of the support cylinder 24 and is forced against the bottom surface of the second ceramic cup 38 where it is welded to the inner wall of the support cylinder 24 to rigidly lock the three ceramic supports 34, 36, 38 within the screen grid cylinder 24.

The several electrode subassemblies are inserted into the support cylinder 24 so that the electrode leads extend through the opening 25 in the side wall of the support cylinder. Furthermore, ceramic cup 36 is positioned within the support cylinder 24 so that the groove 47 in its upper surface 39 will fit over the control grid lead 46 and permit the lip surface 39 of cup 36 to lie flush with the bottom surface of the control grid support disc 34. Likewise, the second ceramic cup 38 is positioned so that groove 57 will fit over the cathode lead 56 and allow the lip surface 53 of the cup 38 to lie flush against the bottom surface of the first ceramic cup 36. When the several parts of the cathode grid assembly of Fig. 2 have been fixed together as described above, this cathode grid assembly cylinder 24 may be mounted on the ceramic side rods 20 and 22 in the desired position. Since the electrode leads 46, 56, 76 and 78 extend laterally from the supporting grid cylinder 24, this cathode grid assembly may be mounted closer to the glass stem portion 12 of the discharge tube. This provides for shorter envelope 10 which is desirable for certain installations.

While certain specific embodiments have been illustrated and described, it will be understood that various changes and modifications may be made therein without departing from the spirit and scope of the invention.

What I claim as new is:

1. A cathode-grid assembly for an electron discharge device, said assembly comprising a tubular support member having an apertured wall portion, an apertured shield electrode structure mounted within said support member at one end thereof providing a shield grid, a control grid unit including an insulator support within said tubular support member and an apertured control elec-

trode fixed thereto and spaced from said apertured shield electrode, a hollow cathode electrode, insulating means mounting said cathode within said tubular support member adjacent said control electrode, a cathode heater filament mounted within said cathode, leads fixed to the ends of said filament and extending through said apertured wall portion of said support member.

2. A cathode grid assembly for an electron discharge device, said assembly comprising a support cylinder, a shield grid electrode comprising a centrally apertured plate coaxially mounted within said support cylinder and closing one end thereof, a control grid unit including a metal grommet forming a control grid electrode and insulating means coaxially mounting said grommet electrode within said support cylinder in spaced relationship to said shield grid plate, a cathode unit including a tubular cathode electrode having a closed end and insulating means coaxially mounting said tubular cathode within said support cylinder with the closed end of said tubular cathode spaced from said control grid electrode on the side thereof opposite from said shield grid plate, a cathode heater unit within said support cylinder and including a heater filament and insulating means mounting said filament within said cathode tube.

3. A cathode discharge device comprising an evacuated envelope, a tubular shield electrode mounted within said envelope, a plate element fixed to and closing one end of said tubular shield electrode, said plate element having a grid aperture therethrough coaxial with said tubular electrode, an annular insulating support disc having a peripheral rib projecting from one surface, said support disc coaxially mounted within said tubular electrode with said peripheral rib in abutment against said apertured plate element to space said disc surface therefrom, a control grid eyelet fixed through the center of said annular support disc, an insulating cathode support cup coaxially mounted within said tubular electrode with the lip of the open end of said cup fixed in abutment to said annular support disc, said cathode support cup having an aperture through the center of the bottom thereof, a tubular cathode electrode having one closed end, said tubular cathode electrode coaxially mounted through bottom aperture of said cathode support cup with the closed end of said cathode electrode axially spaced from said control grid eyelet, an insulating heater filament support mounted within said tubular electrode in abutment to the outer bottom surface of said cathode support cup, a plurality of filament lead elements fixed to said filament support, and a heater filament mounted on said lead elements and extending into the open end of said tubular cathode electrode.

4. A cathode grid assembly for an electron discharge device, said assembly comprising a support cylinder, a wall portion closing one end of said support cylinder, said wall portion having an aperture through the center thereof forming a shield grid electrode, a control grid unit including a ceramic disc coaxially fixed within said support cylinder and a metal eyelet fixed through the center of said ceramic disc and forming a control grid electrode, said ceramic disc having a projection on one side thereof spacing said disc and said control grid eyelet from said shield grid wall portion, a cathode unit including a first ceramic cup coaxially mounted within said support cylinder with the lip of said ceramic cup abutting the other side of said ceramic disc, said ceramic cup having

an aperture through the center of the bottom thereof, and a tubular cathode electrode coaxially mounted through the aperture of said ceramic cup with one end of said cathode electrode axially spaced from said control grid eyelet, and a cathode heater unit including a second ceramic cup coaxially mounted within said support cylinder with the lip of said second ceramic cup abutting the bottom surface of said first ceramic cup whereby the other end of said tubular cathode electrode extends into said second ceramic cup, a pair of spaced conductor leads fixed to said second ceramic cup, and a heater filament mounted between said conductor leads and extending into said other end of said tubular cathode electrode.

5. A cathode discharge device comprising an evacuated envelope, a tubular shield electrode mounted within said envelope, said tubular shield electrode having an aperture in the wall thereof, a plate element fixed to and closing one end of said tubular shield electrode, said plate element having a grid aperture therethrough coaxial with said tubular electrode, an annular insulating support disc having a peripheral rib projecting from one surface, said support disc coaxially mounted within said tubular electrode with said peripheral rib in abutment against said apertured plate element to space said disc surface therefrom, a control grid eyelet fixed through the center of said annular support disc, a first conductor lead fixed to said grid eyelet and extending through the aperture in the wall of said tubular shield electrode, an insulating cathode support cup coaxially mounted within said tubular electrode with the lip of the open end of said cup fixed in abutment to said annular support disc, said cathode support cup having an aperture through the center of the bottom thereof, a tubular cathode electrode having one closed end, said cathode electrode coaxially mounted through the bottom aperture of said cathode support cup with the closed end of said cathode electrode axially spaced from said control grid eyelet, a second conductor lead fixed to said tubular cathode and extending through the aperture in the wall of said tubular shield electrode, an insulating heater filament support mounted within said tubular electrode in abutment to the outer bottom surface of said cathode support cup, a plurality of filament lead elements fixed to said filament support, and a heater filament mounted on said lead elements and extending into the open end of said tubular cathode electrode, said filament lead elements having a portion extending through the aperture in the side wall of said tubular shield electrode in spaced relationship to said first and second conductor leads.

6. A cathode grid assembly for an electron discharge device, said assembly comprising a support cylinder having an aperture in the wall thereof, a wall portion closing one end of said support cylinder, said wall portion having an aperture through the center thereof forming a shield grid electrode, a control grid unit including a ceramic disc coaxially fixed within said support cylinder and a metal eyelet fixed through the center of said ceramic disc and forming an apertured control grid electrode, said ceramic disc having a projection on one side thereof spacing said disc and said control grid eyelet from said shield grid, a conductor lead fixed to said control grid eyelet and extending through said aperture in the wall portion of said support cylinder, a cathode unit including a first ceramic cup coaxially mounted within said support cylinder with the lip of said

ceramic cup abutting the other side of said ceramic disc, said ceramic cup having an aperture through the center of the bottom thereof, and a tubular cathode electrode coaxially mounted through the aperture of said ceramic cup with one end of said cathode electrode axially spaced from said control grid eyelet, a cathode conductor lead fixed to said cathode electrode and extending through the aperture in the wall of said support cylinder, and a cathode heater unit including a second ceramic cup coaxially mounted within said support cylinder with the lip of said second ceramic cup abutting the bottom surface of said first ceramic cup whereby the other end of said tubular cathode electrode extends into said second ceramic cup, a pair of spaced conductor leads fixed to said second ceramic cup, and a heater filament mounted between said conductor leads and extending into said other end of said tubular cathode electrode, said pair of filament conductor leads extending through the aperture in the wall of said support cylinder in spaced relationship to said control grid conductor lead and said cathode conductor leads.

7. A cathode grid assembly for an electron discharge device, said assembly comprising a ceramic disc having an aperture at the center thereof, a metal eyelet fixed through the aperture of said ceramic disc to form a grid electrode, a first ceramic cup mounted coaxial with the ceramic disc

and with the rim of said ceramic cup abutting one face of said disc, a second ceramic cup mounted coaxially to said ceramic disc and said first ceramic cup and with the rim of said second ceramic cup abutting the outer bottom surface of said first ceramic cup, means locking together said ceramic disc, said first ceramic cup and said second ceramic cup to prevent relative movement therebetween, said locking means including a metal plate electrode having an apertured portion, said apertured portion spaced from the other face of said ceramic disc and from said eyelet electrode, said first ceramic cup having an aperture through the center of the bottom portion thereof, a tubular cathode electrode coaxially fixed in said aperture of said first ceramic cup with one end of said tubular cathode electrode closely spaced from said eyelet electrode and the other end of said tubular cathode electrode extending into said second ceramic cup, a pair of heater filament leads fixed to said second ceramic cup, each of said filament leads having a portion extending over the outer surface of the center portion of said second ceramic cup, a cathode heater filament positioned within said tubular cathode, each end of said cathode filament extending through the bottom of said second ceramic cup and fixedly mounted to one of said filament leads.
